US0D1099467S

(12) **United States Design Patent** (10) **Patent No.:** **US D1,099,467 S**
(45) **Date of Patent:** **** Oct. 28, 2025**

(54) **CONFECTIONARY-COATED CONTAINER**

(71) Applicant: **ZURU EDGE LIMITED**, Kowloon (HK)

(72) Inventors: **Mathew Peter Mowbray**, Mid-levels West (HK); **Chung Hyun Lee**, Seoul (KR); **David Johnston Smith**, Auckland (NZ); **Diwata Katrina Dinglasa Santillan**, Auckland (NZ); **Ethan Luke Harrold**, Auckland (NZ); **Ethan Hutchinson**, Dairy Flat (NZ)

(73) Assignee: **Zuru Edge Limited**, Kowloon (HK)

(**) Term: **15 Years**

(21) Appl. No.: **29/974,533**

(22) Filed: **Nov. 22, 2024**

Related U.S. Application Data

(63) Continuation of application No. 29/935,113, filed on Mar. 29, 2024, now Pat. No. Des. 1,056,398, which is a continuation of application No. 17/632,165, filed as application No. PCT/SG2020/050461 on Aug. 7, 2020, now Pat. No. 12,336,548.

CLAIM

The ornamental design for a confectionary-coated container as shown and described.

DESCRIPTION

FIG. 1 is a front elevation view of a confectionery-coated container, showing our new design;
FIG. 2 is a rear elevation view thereof;
FIG. 3 is a top plan view thereof;
FIG. 4 is a front, top, and right side perspective view thereof; and,
FIG. 5 is a front, bottom, and right side perspective view thereof.

(Continued)

The broken lines shown in FIGS. 1-5 illustrate portions of the confectionery-coated container form no part of the claimed design.

1 Claim, 3 Drawing Sheets
